Primary Examiner — Elizabeth Albert(74) *Attorney, Agent, or Firm* — Pearl Cohen Zedek Latzer, LLP(57) **CLAIM**

The ornamental design for a cap for a writing utensil, as shown and described.

DESCRIPTION

FIG. 1 is a front, bottom, right side perspective view of the cap for a writing utensil;

FIG. 2 is a front elevational view thereof;

FIG. 3 is a back elevational view thereof;

FIG. 4 is a left side elevational view, the right side elevational view being a mirror image thereof;

FIG. 5 is a top plan view thereof;

FIG. 6 is a bottom plan view thereof; and,

FIG. 7 is a front, top left side perspective view thereof.

The broken lines showing the pen body in FIGS. 1-4, 6 and 7 are included to show portions that form no part of the claimed design.
